Imp² Embroidering Machine.
N° 79901 Patented Jul. 14, 1868.

UNITED STATES PATENT OFFICE.

JACOB EINHORN, OF NEW YORK, N. Y., ASSIGNOR TO HIMSELF AND JACOB EUGSTER, OF SAME PLACE.

IMPROVEMENT IN EMBROIDERING-MACHINES.

Specification forming part of Letters Patent No. 79,901, dated July 14, 1868.

To all whom it may concern:

Be it known that I, JACOB EINHORN, of the city, county, and State of New York, have invented a new and Improved Embroidery-Machine; and I do hereby declare that the following is a full, clear, and exact description thereof, which will enable others skilled in the art to make and use the same, reference being had to the accompanying drawings, forming part of this specification, in which—

Figure 1, Sheet 1, represents a longitudinal vertical section of my improved embroidery-machine, taken on the plane of the line $x\ x$, Fig. 2. Fig. 2, Sheet 1, is a plan or top view of the same. Fig. 3, Sheet 2, is a detail side elevation of the swinging needle-frame. Fig. 4, Sheet 2, is a detail inverted plan view of the same. Fig. 5, Sheet 2, is a detail vertical section of the needle and its holder, taken on the plane of the line $y\ y$, Fig. 3. Fig. 6, Sheet 2, is a detail vertical section of the sewing-hook and its holder, taken on the plane of the line $z\ z$, Fig. 3. Fig. 7, Sheet 3, is a detail side view, partly in section, of the sewing-hook and the lower part of its holder. Fig. 8, Sheet 2, is a detail face view of the cam by which the sewing-hook is operated. Fig. 9, Sheet 2, is a detail inverted plan view of the device for throwing the needle out of gear. Fig. 10, Sheet 2, is a detail vertical section taken on the plane of the line $x'\ x'$, Fig. 3.

Similar letters of reference indicate corresponding parts.

This invention relates to a new machine for embroidering on gauze or any other suitable fabric; and it consists principally in fitting the devices by means of which the stitches are made in a swinging frame, and in stretching the fabric to be embroidered on a sliding carriage, so that by these means the stitches can be made to follow any desired pattern that may have to be embroidered.

The invention also consists in the arrangement of the needle and hook by means of which the stitches are made, and in the devices for operating and adjusting the same, and for throwing them in or out of gear, which will all be more fully understood from the following description.

A in the drawings represents a stationary frame, of suitable size, in which guides are arranged for a sliding horizontal frame, B, which

has suitable longitudinal rods or rolls, $a\ a$, to which the gauze or fabric to be embroidered is fastened, and between which it is stretched, as is clearly shown in Fig. 2. The frame B can be adjusted by hand or other power on its support A.

C represents a stationary support for holding the stitching apparatus and the shafts for driving the same.

To the support C is hinged an oscillating frame, D, which forms a joint of the real needle-holding frame E, of which full views are given in Sheet 2.

The frame E consists of an upper horizontal bar, b , of a lower horizontal bar, c , of a rear vertical bar, d , by which b and c are connected, of a front vertical arm, e , projecting downward from the front end of b , and of a front vertical arm, f , projecting upward from the front end of c . On the rear bar, d , are horizontal lugs $g\ g$, through which the pins by which the frame E is pivoted to D pass, or to which they are fastened, as is clearly indicated in Fig. 1. The ends of the arms e and f are bent horizontally to the front, as shown in Fig. 3, so that these horizontal parts are in line with each other, as shown in Fig. 3.

Above the bar b project lugs or ears, in which two horizontal shafts, F and G, have their bearings. The shaft F is connected by bevel-gears or otherwise with a vertical shaft, H, which is arranged in rear of and parallel with the rear bar, d , and which at its lower end gears also into a horizontal shaft, I, which has its bearings in lugs projecting from the under side of the bar c . By means of the shafts F and I reciprocating motion is imparted to the needle and sewing-hook, respectively, as will be hereinafter more fully described. They are connected by means of the shaft H, so that their motion may be equal and the numbers of their respective revolutions alike. The shaft H receives rotary motion by means of a belt or otherwise from an arbor, h , which has its bearings on the pivoted end of the frame D in line with the pivot-pins i of the same, as is clearly shown in Fig. 1. As the arbor h receives rotary motion from suitable mechanism, it can transfer the same to the shaft H, as the same is also in line with the pins j , by means of which the frame E is pivoted to the frame D, and as consequently the distance between the axis h

and II is never changed in whatever direction either may be turned or swung.

In the horizontal end *c'* of the upright arm *e*, and in a lug or lugs projecting from the said arm, are the bearings for a vertical tube, *J*, which is fully shown in Fig. 6. Within the tube is arranged a vertical pin, *k*, which is held up by means of a spiral or other spring arranged within the tube *J*, and which is by means of an arm or lever *l* connected with a hook or bell-crank, *L*, which is at its angle pivoted to an arm, *m*, projecting downward from the tubes, and which carries at its free end a hook, as is clearly shown in Figs. 3 and 6.

On the front end of the shaft *F* is mounted, directly above the top end of the pin *k*, a cam, *M*, which is provided with a working-surface, 1, Fig. 8, by means of which it serves to hold down the pin *k* during nearly half the revolution of the shaft *F*. The spring in or on the tube *J* serves to keep the upper end of the pin *k* constantly against the edge of the cam *M*, and as the shaft *F* revolves the cam *M* throws the pin *k* down and holds it down during part of the revolution. When the pin *k* is thus depressed the hook *L* will be swung forward, so as to sweep through and catch a loop held up by the needle, as hereinafter set forth, and as shown in Fig. 3; but when the cam does not depress the rod the hook will be with its point down, or nearly so, so as not to retain a loop.

In the horizontal end of the arm *f*, and in a lug or lugs projecting from the said arm, are the bearings for a reciprocating needle-holder, *N*, to the upper end of which the needle *o* is removably secured. The needle-holder is a vertical rod or tube resting upon the forked end of an oscillating plate, *n*, which is secured to the under side of a plate, *o*, that is hinged to the under side of the bar *c*, as is clearly shown in Figs. 3 and 4. On the rear end of the plate *o* is an upright slotted arm, *p*, Fig. 10, into the slot of which a crank-pin, *r*, that is secured to the front end of the shaft *H*, fits, so that as the shaft *H* is revolved oscillating motion is imparted to the plates *o* and *n*, and consequent reciprocating motion to the needle-holder and needle. A spring, *s*, around the needle-holder serves to keep it down unless it is raised by the plate *n*. The plate *n* is slotted, and is thereby made longitudinally adjustable under the plate *o*, as indicated in Fig. 4. It is by means of suitable levers, *P P*, connected with a spring-catch, *Q*, which, when the upper lever, *P*, is drawn forward, locks it to a stud, *t*, and the plate *n* is thereby withdrawn from the needle-holder, which is thus thrown out of gear. The levers *P P* carry this disengaging apparatus from the lower to the upper part of the frame *E*, as shown in Fig. 3, for the purpose of allowing it to be reached above the fabric. By a suitable spring the plate *n* is thrown forward against the needle-holder as soon as the spring-catch *Q* is again disengaged from the stud. The spring-catch and stud are fully shown in Figs. 3 and 9. The fabric is

between two plates, *v* and *w*, that project respectively from the arm *m* and needle-holding arm *f*, and the plate *v* is adjustable on its holder, as shown in Fig. 7.

The embroidering operation is as follows: The needle is threaded as shown, the thread being by preference passed through an adjustable extension-plate, *a'*, from a bobbin, *R*, hung on the lower part of the frame *E*. As the shaft *I* is revolved, the needle will first be raised, will pass its flattened point through the fabric and through the perforated plates *v w*, and will carry a loop to the hook. The pin *k* is then depressed by the cam *M*, and the hook *L* is thereby thrown forward through the loop that is held up by the needle. The needle then goes down, and as it descends the fabric should be pulled back from the hook; or the frame should be moved forward so as to stretch the last loop in the manner shown in Fig. 1. As the needle comes up again the hook still retains the old loop and the needle passes through it. Then the hook drops the old loop, and, when again thrown forward, takes hold of the new loop, and in this manner the ordinary well-known simple chain-stitch is made. To allow the hook to be always in line with the line to be stitched, it is necessary that it can be turned, and as the needle is flat, so that it can lay close against the side of the hook, it is also necessary that when the hook is turned the needle should be turned in the same manner. This is effected by connecting the tube *J* by means of geared shafts *G*, *G'*, and *G²* with the needle-holder, as shown, so that when the tube, and with it the hook, is turned the needle will also be turned. The hook is formed rather broad, so that it will widen the loop, and it has a grooved outer edge, into which groove the needle slides, so that it will be impossible for the point of the hook to miss the loop.

By having the frame *E* jointed and hinged, as described, it can be moved in any direction, so that the stitches may be arranged in any desired ornamental curved or angular direction, and, if one section of the fabric has been embroidered, the frame *B* is moved so as to bring another section into operation; but if the fabric to be embroidered is not long the frame *B* need not be moved at all, or a movable frame *B* is not then required.

The gear-wheel *b'*, into which the gear on shaft *G²* gears, is fitted around the feathered needle-holder *N*, allowing the same to move freely up and down through it, but causing it to revolve when the shaft *G²* is revolved.

The face of the tube *J* is or should be roughened, so that it can be easily turned by hand.

The size of the needle and of the whole apparatus may be varied with different kinds of work to be done.

Having thus described my invention, what I claim as new, and desire to secure by Letters Patent, is—

1. The arrangement of embroidering mech-

anism, substantially as described, in a jointed swinging horizontal frame, D E, so that ornamental designs may be produced without moving the fabric after each stitch, substantially as herein shown and described.

2. The longitudinally-adjustable frame B, in which the fabric is held, in combination with the jointed swinging needle-frame D E, made as set forth.

3. The rotating cam M, rod k, and lever l, and hook L, in combination with the tube J, and with a spring on or within the same, all made and operating substantially as herein shown and described.

4. The oscillating lever n o, in combination with the crank-shaft I and reciprocating holder

N, all made and operating substantially as herein shown and described, for the purpose of operating the needle in the manner specified.

5. The longitudinally-adjustable oscillating lever n, in combination with the levers P P, and the spring-catch Q or its equivalent, all made and operating so as to allow the needle to be easily thrown in or out of gear.

6. The application of the hook L and needle O, operated by the mechanism described, for working a chain-stitch, for the purposes specified.

JACOB EINHORN.
